UNITED STATES PATENT OFFICE.

FRANK A. ADAMS, OF ROCHESTER, NEW YORK, ASSIGNOR TO B. C. OLNEY, OF ROME, NEW YORK, AND J. O. DAILEY, OF ROCHESTER, NEW YORK.

CLOTHES-WASHING MACHINE.

Application filed September 30, 1921. Serial No. 504,411.

To all whom it may concern:

Be it known that I, FRANK A. ADAMS, a citizen of the United States of America, residing at Rochester, in the county of Monroe and State of New York, have invented certain new and useful Improvements in Clothes-Washing Machines, of which the following is a specification.

My invention relates to clothes washing machines, and is an improvement on the construction disclosed in my Patent No. 1,406,137, patented February 7th, 1922, the purpose of the present structure being primarily to afford an arrangement for easily and efficiently rinsing clothes after the washing operation.

More particularly, the invention has for its purpose to provide a water power operated machine in which the exhaust water from the motor can be diverted into the clothes receptacle during the rinsing operation, by a controlling device that can be readily adjusted by the operator.

A further purpose of the improvement is to apply the rinsing principle as set forth above to a mechanism such as embodied in my former application, utilizing the chamber which normally functions as an insulating air space to conduct the rinse water to the top of the receptacle during the rinsing operation.

To these and other ends, the invention comprises the structure that will be fully set forth in the following description, in conjunction with the accompanying drawings, the novel features being pointed out in the claims following the description.

In the drawings:

Figure 1 is a vertical sectional view of a clothes washing machine embodying a preferred arrangement of my invention;

Figure 2 is a sectional view on the line 2—2 of Figure 1, with the controlling valve positioned to divert the exhaust water to the conductor for rinsing;

Figure 3 is a sectional view similar to Figure 2, with parts broken away, and showing the controlling valve turned so as to divert the exhaust water to the outlet and drain the conductor;

Figure 4 is a detail sectional view on line 4—4 of the carrier and baffle;

Figure 5 is a rear elevation of the valve mechanism;

Figure 6 is a sectional view through the valve mechanism; 55

Figure 7 is an end view of the controlling valve and exhaust chamber;

Figure 8 is a detail view in elevation of the controlling valve; 60

Figure 9 is a vertical sectional view of a modified form of machine with the invention applied thereto, and

Figure 10 is a detail sectional view of the carrier and baffle disclosed in Figure 9. 65

The underlying principle of the invention as set forth in the following description is applicable to various types of washing machinery, and it is to be understood that the constructions disclosed herein are 70 intended only as exemplary embodiments of practicable, operative machines, although the invention can be adapted to various other forms of construction.

In the machine shown in Figures 1 to 8, 75
1 designates a clothes receptacle, in which is arranged a water agitator, in the present instance consisting of cups 2 mounted on a carrier 3, upon which is also fixed a piston 4 movable in the cylinder 5, the piston 4 being caused to travel back and forth in the cylinder 5 by water pressure controlled by a valve mechanism which forms no part of the present invention and is fully set forth in my patent previously referred to. The 80
chief accomplishment which the present invention is intended to bring about is to readily and efficiently utilize the waste or exhaust water from the water motor for rinsing the clothes, and I will now describe the 85
mechanism by which this end is attained. 90

Surrounding the water motor just mentioned is a housing 6, which has an outlet or opening 7 at the top, and serves during the normal operation of the machine to insulate the heated water in the receptacle 1 from the cold water in the motor, as set forth in my previously mentioned application. The housing 6 also constitutes a water conductor, to convey the rinsing water from the exhaust chamber to the upper central portion of the receptacle, and to this end the exhaust chamber 8 has a passage 9 leading to a valve chamber which is provided with ports 10 and 11. 100

The port 10 communicates with the water conductor 6 leading to the top of the receptacle, and the port 11 leads to the waste or 105

discharge opening 12. 13 designates a valve, preferably of the rotary type, and operable to place the exhaust chamber in communication either with the rinsing water conductor, as shown in Figure 2, or in communication with the discharge, as in Figure 3. The valve 13 is turned by means of a finger piece 14 and is provided with a lug 15 which cooperates with stops 16 to limit its movement in opposite directions, 17 being a spring which serves to hold the valve tightly in its seat.

In the operation of the mechanism, the receptacle 1 is filled with hot water and the necessary amount of soap, the clothes being positioned in the receptacle, and the valve 13 is turned to the position illustrated in Figure 3. Then upon turning on the water to the motor, the cups 2 are reciprocated, and the water from the motor is discharged at the waste opening 12. When this washing operation is completed and it is desired to rinse the clothes, valve 13 is turned to the position illustrated in Figure 2, causing the exhaust water from the motor to pass upwardly through the conductor 6 and to be discharged at the top thereof through the opening 7. In order to deflect the water as it passes upwardly from the conductor 6 and to divert it downwardly onto the clothes, there is provided a baffle 18 mounted on the carrier 3 and in the path of the upwardly directed stream of water. This causes the rinse water to be directed downwardly over substantially the entire top surface of the clothes from a point at the upper central portion of the receptacle, causing a thorough rinsing, while at the same time the cups 2 are in operation moving upwardly and downwardly, and causing a complete agitation of the water and clothes.

In some instances, it may be desirable to utilize this same rinsing principle with machines in which the agitating devices are operated by other than a fluid pressure motor, and such an adaptation is illustrated in the modified form of Figure 9 in which the cups 19 are mounted on a hollow carrier 20 that is operated upwardly and downwardly from an electric motor, driving through a pulley 21 to a crank mechanism and connecting rod 22 pivoted to the carrier 20. With such an arrangement, a flexible hose 23 or other suitable connection may be made with the lower end of the carrier 20 to permit conveying rinsing water upwardly therethrough. At its upper end, the carrier 20 is provided with openings 23 through which the water issues during the rinsing operation, and a baffle 24 against which it is directed and which serves to divert it downwardly onto the clothes.

It will be understood that other changes and modifications may be made in the construction shown, without departing from the

purpose and spirit of the invention, and this application is intended to cover any such departures as may come within the intended scope of the invention and of the following claims.

I claim:

1. In a clothes washing machine, the combination with a receptacle, of a water agitator movable in the receptacle, a hydraulic motor arranged in the receptacle for operating said agitator, a housing surrounding said motor and spaced therefrom to afford a water conductor with an outlet at the top, an exhaust chamber into which exhaust water passes from the hydraulic motor, and means for establishing communication between said exhaust chamber and said water conductor. 70

75

2. In a clothes washing machine, the combination with a receptacle, of a water agitator movable in the receptacle, a hydraulic motor arranged in the receptacle for operating said agitator, a housing surrounding said motor and spaced therefrom to afford a water conductor with an outlet at the top, 80 an exhaust chamber into which exhaust water passes from said hydraulic motor, a valve chamber having one port leading to the water conductor and another port leading to a discharge, and a valve operable to establish 85 communication between the exhaust chamber and either of said ports. 90

3. In a clothes washing machine, the combination with a receptacle, of a water agitator movable in the receptacle, a hydraulic 100 motor arranged in the receptacle for operating said agitator, a housing surrounding said motor and spaced therefrom to afford a water conductor with an outlet at the top, an exhaust chamber into which exhaust 105 water passes from said hydraulic motor, a valve chamber having one port leading to the water conductor and another port leading to a discharge, a valve operable to establish 110 communication between the exhaust chamber and either of said ports, and means for draining the water conductor when the exhaust chamber and discharge are in communication. 115

4. In a clothes washing machine, the combination with a receptacle, of a water agitator movable in the receptacle, a hydraulic motor arranged in the receptacle for operating said agitator, a housing surrounding said motor and spaced therefrom to afford a 120 water conductor with an outlet at the top, and means permitting exhaust water from said motor to pass to the water conductor. 125

5. In a clothes washing machine, in combination with a receptacle, of a water agitator movable in the receptacle, a hydraulic motor arranged in the receptacle for operating said agitator, a housing surrounding said motor and spaced therefrom to afford a water conductor with an outlet at the top, 130

- an exhaust chamber into which exhaust water passes from said hydraulic motor, a valve chamber having one port leading to the water conductor and another port leading 5 to a discharge, a valve adapted to establish communication between the exhaust chamber and either of said ports, said valve chamber also having a drain port adapted to be placed in communication by said valve with the 10 water conductor when communication between the water conductor and exhaust chamber is closed.
6. In a clothes washing machine, the combination with a receptacle, of a water agitator movable in the receptacle, a hydraulic motor for operating said agitator, a water conductor arranged to discharge a body of water at the upper portion of the receptacle, an exhaust chamber into which exhaust 15 water passes from said hydraulic motor, a valve chamber having one port leading to the water conductor and another port leading to a discharge, and a valve operable to establish communication between the exhaust chamber and either of said ports.
7. In a clothes washing machine, the combination with a receptacle, of a water agitator movable in the receptacle, a hydraulic motor for operating said agitator, a water conductor arranged to discharge a body of water at the upper portion of the receptacle, an exhaust chamber into which exhaust 20 water passes from the hydraulic motor, and means for establishing communication between said exhaust chamber and said water conductor.
8. In a clothes washing machine, the combination with a receptacle, of a water agitator movable in the receptacle, a hydraulic motor arranged in the receptacle for operat- 25
- ing said agitator, a housing surrounding said motor and spaced therefrom to afford a water conductor with an outlet at the top, an exhaust chamber into which exhaust water passes from the hydraulic motor, means for establishing communication between said exhaust chamber and the water conductor, and means for draining the water conductor when not in communication with said exhaust chamber. 30
9. In a washing or like machine, the combination with a receptacle, means for agitating the contents thereof comprising a fluid actuated motor provided with inlet and exhaust ports, and a fluid conductor connecting the exhaust port with the interior of the receptacle. 35
10. In a washing or like machine the combination of a receptacle, means for agitating the contents thereof comprising a fluid actuated motor provided with inlet and exhaust ports, and means whereby the exhaust fluid may be discharged into the receptacle or outside thereof at will. 40
11. In a washing or like machine, the combination of a receptacle, means for agitating the contents thereof comprising a fluid actuated motor provided with inlet and exhaust ports, a valve chamber having a port affording communication with the exhaust 45 port of the motor, a port communicating with the receptacle, and a port arranged to discharge outside of said receptacle, and a valve in said valve chamber adapted to establish communication between the exhaust port and either of said ports controlled by it at will. 50

In witness whereof, I have hereunto signed my name.

FRANK A. ADAMS.
